UNITED STATES PATENT OFFICE

WILLIAM OVESON, OF ROSEAU, MINNESOTA

STUMP PULLER

Application filed February 15, 1929. Serial No. 340,119.

This invention relates to a device for pulling stumps, trees and the like, the general object of the invention being to so construct and arrange the parts that the lift is perpendicular instead of horizontal so that the pulling force is exerted in a vertical direction, which is the logical one, as the natural growth of a tree's roots is to resist wind from the sides so that the roots offer more resistance when a stump is pulled by means which exert the pulling force in a horizontal direction than they do if the force is a vertical one, as the roots will more readily give and there is practically no resistance except from the weight of the tree or stump and the dirt resting on top of the roots.

Another object of the invention is to provide means whereby the cable can be wound on the drum by either hand power or motive power and also to provide braces for the upper end of the crane which may be adjusted to suit conditions.

This invention also consists in certain other features of construction and in the combination and arrangement of the several parts, to be hereinafter fully described, illustrated in the accompanying drawings and specifically pointed out in the appended claim.

In describing the invention in detail, reference will be had to the accompanying drawings wherein like characters denote like or corresponding parts throughout the several views, and in which:—

Figure 1 is an elevation of the invention.
Figure 2 is a top plan view thereof.

Figure 3 is a front view.

In these views, the numeral 1 indicates a sled-like base on which the various parts of the device are arranged so that the device can be easily transported from place to place. A crane forming beam 2 is diagonally supported on the base with its lower end fastened to the base and with its upper end extending well beyond the rear of the base, a pair of braces 3 being connected with an intermediate portion of the beam and to the base.

Truss rods 4 are connected with the base adjacent the bottom of the beam and these truss rods pass over a block 5 on the beam at about the center thereof and have their up-

per ends connected with the bracket 6 attached to the upper end of the beam. A shaft 7 is journaled in the uprights 8 on the front of the base and said shaft carries the drum 9 for the cable 10. The drum is provided with the usual brake means 11 which are operated by the brake lever 12 and a pulley 13 is loosely arranged on the drum shaft and a belt 14 passes over this pulley and over a pulley 15 which is suitably connected to the shaft of a motor 16 on the base. Friction clutch means, shown generally at 17, are provided for connecting the pulley 13 with the drum shaft or disconnecting it therefrom, the lever for such clutch means being shown at 18.

A shaft 19 is journaled in the uprights and has a hand wheel 20 on its outer end, said shaft carrying a pinion 21 which meshes with a gear 22 on the drum. Thus the drum can be either rotated by hand through means of the hand wheel 20 or through the motor through the belt and pulleys. It will, of course, be understood that the clutch means must be in operative position when the drum is being rotated from the motor, but when the drum is to be rotated by hand, the clutch means should be in inoperative position.

The cable 10 passes upwardly above the beam and under a guiding pulley 23 and over a sheave 24 carried at the front end of the beam. The cable then passes downwardly under a sheave 25 in the block 25, then upwardly over a sheave 26 in the block 26 which is attached to the beam, and then downwardly over another sheave 25 in the block 25 and finally the cable passes upwardly and is connected to a ring 27 at the lower side of the block 26.

A pair of brace legs 28 have their upper ends pivotally connected with the upper end of the beam, as shown at 29, so that these legs can be adjusted to any angle to support any lifting strain on the crane.

From the foregoing it will be seen that the pull exerted by the cable on the block which is attached to the stump or tree is in a vertical direction which, as before stated, is the logical one, as the roots of a stump or tree will offer least resistance to such a pull.

It is thought from the foregoing description that the advantages and novel features of the invention will be readily apparent.

It is to be understood that changes may be made in the construction and in the combination and arrangement of the several parts, provided that such changes fall within the scope of the appended claim.

What I claim is:—

- 10 Stump pulling apparatus comprising a base, a beam mounted at its forward end upon the base, the beam being upwardly and rearwardly inclined and extending a considerable distance beyond the rear end of the base, braces at the rear end of the base for supporting the beam inwardly of its rear end, bracing members pivotally connected at their upper end to the beam at opposite sides of the rear end thereof and extending downwardly and rearwardly therefrom and diverging outwardly with relation to each other, a pulley mounted at the upper rear end of the beam, a block at the upper rear end of the beam, a block below the first mentioned block, a pulley mounted in the first mentioned block, a shaft mounted upon the base at the forward end thereof, a drum upon the shaft, a cable connected to the drum to be wound thereon and unwound therefrom, and
- 15 means for rotating the shaft comprising a motor mounted upon the base and between the drum and the rear end of the base, an idle pulley mounted upon the upper side of the beam between the ends thereof, the cable being passed beneath said idle pulley and over the pulley first mentioned, pulleys rotatably mounted in the second mentioned block, the cable being led downwardly from the first mentioned pulley and beneath one of the
- 20 pulleys of the last mentioned block, thence upwardly and over the pulley of the first mentioned block, and thence downwardly and beneath the other pulley of the second mentioned block and upwardly therefrom and
- 25 anchored to the first mentioned block, the blocks being in vertical alinement with each other between the first mentioned braces, and the downwardly and rearwardly inclined relatively diverging braces, and means upon
- 30 the last mentioned block for connection of the block with means to be anchored to the stump to be pulled.

In testimony whereof I affix my signature.

WILLIAM OVESON.
